UNITED STATES PATENT OFFICE.

HERBERT O. RUSSELL, OF LOS ANGELES, CALIFORNIA, AND CHARLES L. PAULUS, OF DAYTON, OHIO.

BOWDEN TRIGGER CONTROL FOR MACHINE GUNS.

Application filed June 9, 1922. Serial No. 567,073.

To all whom it may concern:

Be it known that we, HERBERT O. RUSSELL and CHARLES LEIGH PAULUS, citizens of the United States, residing, respectively, at Los Angeles and Dayton, in the counties of Los Angeles and Montgomery, and States of California and Ohio, have invented certain new and useful Improvements in Bowden Trigger Controls for Machine Guns, of which the following is a specification.

This invention relates to a trigger control for machine guns, the object in view being to provide simple means for operating a Browning machine gun from a distance by means of a flexible Bowden wire control.

A further object in view is to provide a trigger operating device which is capable of being quickly mounted upon a part of the Browning machine gun so that it will readily operate the trigger thereof while at the same time forming a protection for said trigger.

With the above and other objects in view the invention consists in the novel construction, combination and arrangement herein fully described, illustrated and claimed.

In the accompanying drawings:

Figure 1 is a fragmentary side elevation of the rear portion of a machine gun showing the trigger operating means of this invention applied thereto.

Figure 2 is a rear elevation of the same.

Referring to the drawings:

The improved trigger operating mechanism embodies a mounting bracket 1 having a circular clamping portion 2 with projecting ends 3 through which are inserted one or more fasteners 4 to securely clamp the bracket upon the buffer housing 5 projecting from the rear end of the machine gun 6.

The lower portion of the mounting bracket is formed into a housing 7 adapted to receive and protect a portion of the trigger 8 of the machine gun as shown in Figure 1. Mounted within the housing 7 upon a pivot is a trigger operating arm 10 which is preferably composed of two side pieces or members in spaced relation to each other and connected at the free end of the arm by a roller 11 carrying anti-friction roller 12 which operates against the inner curved or concave side of the trigger as shown in Fig-

ure 1. The side plates of the housing 7 are formed with slots 13 to permit the necessary movement of the roller 11.

Attached to the trigger operating arm 10 by a suitable means 14 is a flexible wire or cable 15 which may lead to a point any necessary distance from the gun 6. The wire or cable 15 passes through a tubular casing 16 which is attached at one end to the housing 7, being set into a socket 17 therein. A spring 18 is placed behind the trigger operating arm 10 for the purpose of returning said arm to the normal position shown in Figure 1 after the cable or wire 15 has been pulled to operate the trigger of the machine gun.

Having thus described our invention, we claim:

1. In combination with a machine gun, a mounting bracket adapted to be clamped to the buffer housing of the gun, a housing carried by said bracket and formed to receive a portion of the machine gun trigger, a trigger-operating arm pivotally mounted in said housing with its free end engaging said trigger, and an operating cable attached to said arm.

2. In combination with a machine gun, a mounting bracket adapted to be clamped to the buffer housing of the gun, a housing carried by said bracket and formed to receive a portion of the machine gun trigger, a trigger-operating arm pivotally mounted in said housing with its free end engaging said trigger, and an operating cable attached to said arm, said cable including a tubular casing attached to said housing.

3. In combination with a machine gun, a mounting bracket adapted to be clamped to the buffer housing of the gun, a housing carried by said bracket and formed to receive a portion of the machine gun trigger, a spring-retracted trigger-operating arm pivotally mounted in said housing with its free end engaging said trigger, and an operating cable attached to said arm.

In testimony whereof we affix our signatures.

HERBERT O. RUSSELL.
CHARLES L. PAULUS.
